(57) **CLAIM**

The ornamental design for a horticulture grow light, as shown and described.

DESCRIPTION

FIG. 1 is a perspective view of a horticulture grow light, as viewed from below, showing my new design;

FIG. 2 is a perspective view of the light shown in FIG. 1, as viewed from above;

FIG. 3 is a left side view of the light shown in FIG. 1;

FIG. 4 is a right side view of the light shown in FIG. 1;

FIG. 5 is a front elevation view of the light shown in FIG. 1;

FIG. 6 is a rear elevation view of the light shown in FIG. 1; FIG. 7 is a bottom plan view of the light shown in FIG. 1; FIG. 8 is a top plan view of the light shown in FIG. 1; FIG. 9 is a perspective view thereof, as viewed from below, with its lower reflective surfaces removed for clarity of illustration;

FIG. 10 is a perspective view of the light shown in FIG. 9, as viewed from above;

FIG. 11 is a left side view of the light shown in FIG. 9;

FIG. 12 is a right side view of the light shown in FIG. 9; FIG. 13 is a front elevation view of the light shown in FIG. 9;

FIG. 14 is a rear elevation view of the light shown in FIG. 9;

FIG. 15 is a bottom plan view of the light shown in FIG. 9; FIG. 16 is a top plan view of the light shown in FIG. 9; FIG. 17 is a perspective view thereof, as viewed from below, with its upper light socket enclosure removed for clarity of illustration;

FIG. 18 is a perspective view of the light shown in FIG. 17, as viewed from above;

FIG. 19 is a left side view of the light shown in FIG. 17;

FIG. 20 is a right side view of the light shown in FIG. 17; FIG. 21 is a front elevation view of the light shown in FIG. 17;

FIG. 22 is a rear elevation view of the light shown in FIG. 17;

FIG. 23 is a bottom plan view of the light shown in FIG. 17; and,

FIG. 24 is a top plan view of the light shown in FIG. 17. The broken-line disclosure shown in the views is understood to represent portions of the article in which the claimed design is embodied, but which form no part of the claimed design.
